INSPECTION TELESCOPE

Ludwig Streifeneder, Chicago, Ill.

Application November 5, 1956, Serial No. 43,655

Term of patent 14 years

(Cl. D57—1)

Fig. 2.

Fig. 1.

Fig. 3.

Fig. 4.

Figure 1 is a side elevation of an inspection telescope showing my new design and with the tube portion broken away to indicate indeterminate length;

Figure 2 is an end view of the telescope shown in Figure 1;

Figure 3 is an enlarged top view of the tube end portion shown in Figure 1; and

Figure 4 is an end view taken from the left of Figure 3.

The other side of the telescope not shown is similar to the side shown.

I claim:

The ornamental design for an inspection telescope, as shown and described.
